SPRING BUMPER AND DRAFT GEAR

Robert A. Shields, Berwick, Pa., assignor to American Car and Foundry Company, New York, N. Y., a corporation of New Jersey

Application September 16, 1941, Serial No. 410,973

15 Claims. (Cl. 213—9)

This invention relates to improvements in spring bumpers and draft gear and in particular to such gear when employed with mine and similar industrial cars.

In mine and industrial cars it has been practically impossible to standardize equipment due to varying track gauges and local conditions influencing the height, width and weight of the cars. As a result practically all mine and industrial cars have been built more or less to customers' specifications with the result that the bumpers and draft gear have varied tremendously both in construction and in operation. It is an object, therefore, of the present invention to provide an improved bumper and draft gear assembly which may be readily modified to fit varying conditions arising in various installations.

A further object of the invention is the provision of a new improved bumper and draft gear assembly in which a more or less standard bumper and draft element may be built to receive varying sizes, number and capacities of resilient means for resisting shock.

A still further object of the invention is the provision of a new and improved draft gear and bumper assembly which may be readily and easily modified to give varying resistance to bumper or draft shocks.

A yet further object of the invention is the provision of a new and improved spring assembly in which the springs are handled in pairs as units.

Yet another object of the invention is the provision of a new and improved bumper and draft assembly in which paired resilient units engage a single cross member locking the entire assembly to the car structure.

These and other objects of the invention will be apparent to persons skilled in the art from a study of the following description and accompanying drawings, in which:

Figure 1 is a plan view of the improved construction with parts broken away and parts in section to better disclose the internal construction;

Fig. 2 is a sectional view taken substantially on the longitudinal center line of the construction shown in Fig. 1;

Fig. 3 is a partial end and partial sectional view taken on line 3—3 of Fig. 1;

Fig. 4 is a longitudinal sectional view taken through a resilient unit with the cross member in position;

Fig. 5 is a partial side sectional view similar to Fig. 2 but showing a slight modification producing the same spring action, and

Fig. 6 is a partial side sectional view similar to Figs. 2 and 5 but showing a still further modification producing a modified spring action.

Referring now to the drawings in detail, it will be seen that the improved construction consists mainly of a flanged bumper and draft element A, carried by side sill elements B and locked in position by a single cross member or key C which forms an anchor for paired spring elements D. The flanged bumper and draft gear element is constructed, as clearly shown in the figures, with a curved vertically extending front face 2 merging into rearwardly extending upper and bottom flanges 4 and 6 respectively. The upper flange of the bumper and draft element is provided with a slot 7 adapted to receive a U-shaped strap 8 welded or otherwise secured to the top flange and with the lower arm thereof underlapping the top flange, as clearly shown in Fig. 2, thus effectively interlocking the two parts. The outer portions of the U-shaped strap as well as the top and bottom flanges of the bumper and draft element are provided with openings 10 adapted to receive a coupling pin (not shown), by means of which draft forces may be transferred to the bumper and draft element. As clearly shown in Figs. 1 and 2 the front face of the bumper and draft element is reinforced by a heavy strap 12 to which is attached at the ends or any desired portion thereof wedge shaped blocks 14 in order that a flat back surface may be provided to transfer bumping shocks to the resilient units later to be described. As clearly shown in Figs. 1 and 2, the rear portions of the top and bottom flanges of the bumper and draft element are tied together by vertically extending plates 15 and 16 welded together and forming the legs and arms respectively of T-shaped reinforcements extending between the flanges and to transfer draft forces from the bumper and draft element to the spring units later to be described.

The flanged bumper and draft element previously described may be mounted in any suitable manner upon the car structure but in the present instance it is mounted upon and carried by the lower flanges 18 of side sill elements B, previously referred to. The webs 19 of the side sill elements are attached in any suitable manner to the side sills of the car, while the upper flanges 20 of the side sill elements form a support for a housing plate 21 covering the bumper element and extending down over the inner end as at 22, then horizontally rearward as at 23 for attachment to car floor 24, all as clearly shown in Figs. 2 and 3. Thus the bumper element is fully pro-

tected from lading in the car and any tilting tendency under draft action is resisted by the housing and by flanges 18 and 20 of the side sill elements. The side sill elements, as well as the side sills, are slotted as at 25 (Figs. 1 and 3) to receive the cross member or key C which, when in position, will be held against removal by locking rings 26 pressed into position and as clearly shown in Figs. 1 and 3.

As shown in Fig. 1 two pairs of resilient units are provided and each of these units consists of a front U-shaped strap and a rear U-shaped strap. The front U-shaped strap is formed with a flat web portion 30 and rearwardly directed arms 32 slotted near their extremities as at 34 and with the slots of sufficient width as to accommodate the cross member C and of a length to permit the desired movement under buff forces. The farther or free ends of the arms of the forward straps are joined together by means of cross bars 36 which effectively tie the ends of the side arms together and form stops to cooperate with followers on the rear half of the spring unit. The rear U-shaped straps are of similar formation with a web portion 40, side arms 42, elongated slots 44 and cross bars 46 joining the free ends of the side arms together to prevent spreading and to transfer forces to a follower block yet to be described. Front and rear spring seats are formed by plates 50 to which are welded short lengths of pipe 52 forming centering means for the remote ends of front springs 54 and rear springs 56. The inner or near end of spring 54 is held in position by a short length of pipe 58 welded or secured to a follower block 60 of such a length as to engage at its ends with cross bars or stops 46 and having its center portion enlarged as at 61 to engage the cross member or key C as clearly shown in Figs. 2 and 4. The inner or near end of rear spring 56 is held centered by means of a short pipe 62 welded or otherwise secured to follower 64 having its ends bearing upon stops or cross bars 36 and with its central portion enlarged as at 65 to bear upon the cross member or key C previously referred to. It will be seen from the preceding description that a spring unit has been formed consisting of a front and a rear U-shaped strap with the arms facing each other and overlapping and tied together against separation by the cross bars or stops 36 and 46. Also that each unit consists of front and rear springs and spring retaining means, some of which act as followers engaging the stops or cross bars as well as the cross member or key in the final assembly. It will be obvious that by modifying the width and position of the cross bars 36 and 46 on the straps that modified spring action may be obtained.

In assembling the entire construction the U-shaped straps are brought into proper relation after which one set of cross bars or stops are welded in place, thus tying the two straps together against separation, then the followers and spring centering means and springs are brought into proper relation and the entire assembly compressed slightly and inserted in the bumper and draft element between stops 14 and 16. With the spring units in this position a gap is left between the followers 60 and 64 since these followers are held by the stops 46 and 36 respectively, then the bumper and draft member with the paired spring units in position is slid into the car upon flanges 18 of the side sill elements until cross member or key C can be inserted. Insertion of the key or cross member then effectively locks 75

the entire assembly to the car and maintains the bumper and draft element in a central position.

Application of a bumping force to the bumper face will cause the entire assembly to move rearwardly with stops 14 acting through web 30 directly upon spring 54 which is held against movement by follower 60 resting upon the cross member or key C. In the meantime arms 32 of the forward U-shaped strap have moved rearwardly as allowed by slots 34 and stops or cross bars 36 have moved follower 64 rearwardly compressing rear spring 56 which, however, is held against movement by means of the rear U-shaped strap since arms 42 thereof are engaged over the cross member or key. The rear stops 16, of course, have in the meantime moved away from web 40 and serve no useful function under buffing action. Application of a draft force to the combined bumper and draft element will cause the entire assembly to move outward. In this case the T-shaped elements will through web 40 directly compress the rear spring 56 against follower 64 which is held by the cross member or key. In the meantime the outwardly moving arms 42 of the rear U-shaped strap will move forward causing cross bar 46 to move follower 60 forward compressing forward spring 54 which is held by its U-shaped strap arms 32 engaging the cross member or key. Thus it will be seen under both draft and buff both springs of both pairs act to resist movements of the combined bumper and draft element. It will, of course, be obvious that if the stops 46, for instance, are attached to the side arms 42 at points nearer the web of the U-shaped strap, then they will not immediately contact follower 60 upon forward movement of the arms and springs 56 will absorb the first draft force with springs 54 coming into action later dependent on placement of stops 46. Thus a graduated draft action can be obtained. The same is true if a graduated buff action is desired, in which case stops or cross bars 36 would be shifted nearer web 30 and attached to side arms 32 at points other than those shown.

In some cases it may be objectionable, due to bending, to have the side arms 32 and 42 act in compression to transfer a part of the bumping and draft forces to certain of the spring elements and this may be readily overcome by welding or otherwise securing stops to the upper and lower flanges of the draft and bumper element. In the modification shown in Fig. 5 upper and lower stops 70 and 72 respectively are secured to the upper and lower flanges 4 and 6 of the combined bumper and draft element. These stops are shown of a length to substantially occupy the space between followers 60 and 64, thus upon movement of the bumper and draft element under buffing forces the stops 70 and 72 will move to the rear, that is, to the left of Fig. 5, and will cause follower 64 to compress spring 56, the movement of which is resisted by the arms 42 acting in tension. In the meantime the front spring 54 has been compressed as described in connection with Figs. 1 to 4 inclusive but in this case the side arms 32 do not carry any load whatsoever but merely act as guides and a spring retaining means. The reverse action is true under draft forces, in which case stops 70 and 72 will move follower 60 forward compressing spring 54. Thus all compressing strains are carried by the combined bumper and draft element which can easily be made strong enough to withstand any strains to which it may be subjected.

As stated previously, it may be desired to modi-

fy the spring action, that is, to give a graduated spring action on either buff or draft. Since the graduated spring action is most desirable on draft, the manner of obtaining this has been shown in Fig. 6. In this case upper and lower stops 80 and 82 are shown secured respectively to upper and lower flanges 4 and 6 of the bumper and draft element. Since a graduated draft action is desired these stops are of a length chosen in accordance with the spring action desired and do not occupy the entire space between the followers 60 and 64. However, they are normally in direct contact with follower 64 in order that when buff forces are to be absorbed they will cause follower 64 to move to the rear immediately, thus compressing springs 56 in unison with springs 54 compressed directly by the bumper as previously described in connection with Figs. 1 to 5 inclusive. When, however, draft forces are to be absorbed, the bumper and draft element will move outwardly, that is, to the right of Fig. 6 and spring 56 will be compressed directly by the T-shaped members formed by plates 15 and 16 and as described in connection with Figs. 1 to 4 inclusive. The stops 80 and 82, however, will be moving outwardly without resistance until such time as they strike follower 60 which will then be moved forwardly or to the right of Fig. 6 compressing spring 54 exactly in the same manner as described in Figs. 1 to 5 inclusive. It will be seen, however, that spring 56 will have absorbed a certain amount of the draft force before any can be transmitted to spring 54 and that spring 56 will always assume the major portion of the load with 54 assuming a minor portion and the proportion of the load absorbed by the springs of each pair will be dependent upon the predetermined length of stops 80 and 82. It is obvious that if a modified buff spring action is desired, then the stops 80 and 82 would be positioned so as to pick up follower 64 at a time subsequent to the initial rearward movement of the bumper and draft element.

In connection with Figs. 5 and 6 it is, of course, understood that the remainder of the structure, not shown, is identical or substantially identical to that described in connection with Figs. 1 to 4 inclusive. It is also to be understood that while the invention has been described more or less in detail with specific reference to three modifications, other modifications as well as rearrangements of parts may be made by persons skilled in the art and all such modifications and rearrangements of parts are contemplated as will fall within the scope of the appended claims defining my invention.

What is claimed is:

1. In a combined bumper and draft gear for mine or other industrial cars having side sill elements, a flanged bumper and draft element carried by the side sill elements and longitudinally slidable relative thereto, a cross member extending across the bumper element between the flanges thereof and carried by said side sill elements against longitudinal movement relative thereto, U-shaped straps slidably engaging said cross member and located forward and rearward thereof, resilient means interposed between the web portions of said straps and said cross member and urging said straps apart, and means for transferring bumping and draft forces from said bumper and draft element to said straps and resilient means.

2. In a combined bumper and draft gear for mine or other industrial cars having side sill ele-

ments, a flanged bumper and draft element carried by the side sill elements and longitudinally slidable relative thereto, a cross member extending across the bumper element between the flanges thereof and carried by said side sill elements against longitudinal movement relative thereto, U-shaped straps slidably engaging said cross member and located forward and rearward thereof, resilient means interposed between the web portions of said straps and said cross member and urging said straps apart, and means for transferring bumping and draft forces from said bumper and draft element to said resilient means, said means including stops on said straps and followers normally engaging said cross member and alternately movable by said stops.

3. In a combined bumper and draft gear for mine or other industrial cars having side sill elements, a flanged bumper and draft element carried by the side sill elements and longitudinally slidable relative thereto, a cross member extending across the bumper element between the flanges thereof and carried by said side sill elements against longitudinal movement relative thereto, U-shaped straps slidably engaging said cross member and located forward and rearward thereof, resilient means interposed between the web portions of said straps and said cross member and urging said straps apart, and means for transferring bumping and draft forces from said bumper and draft element to said resilient means, said means including stops on said bumper and draft element and followers normally engaging said cross member and alternately movable by certain of said stops.

4. In a combined bumper and draft gear for mine or other industrial cars having side sill elements, a flanged bumper and draft element carried by the side sill elements and longitudinally slidable relative thereto, a cross member extending across the bumper element between the flanges thereof and carried by said side sill elements against longitudinal movement relative thereto, U-shaped straps slidably engaging said cross member and located forward and rearward thereof, resilient means interposed between the web portions of said straps and said cross member and urging said straps apart, and means for transferring bumping and draft forces from said bumper and draft element to said resilient means, said means including stops on said bumper and draft element and followers normally engaging said cross member and alternately movable by certain of said stops, said certain of said stops engaging certain of said followers subsequent to transfer of said forces to part of said resilient means.

5. In a combined bumper and draft gear for mine or other industrial cars having side sill elements, a flanged bumper and draft element carried by the side sill elements and longitudinally slidable relative thereto, a cross member extending longitudinally across the bumper element between the flanges thereof and carried by said side sill elements against longitudinal movement relative thereto, and means including transversely spaced resilient elements carried between the flanges of the bumper element on the inner and outer sides of said cross member and each cooperating with the cross member to resist both bumping and draft forces acting upon the bumper element.

6. In a combined bumper and draft gear for mine or other industrial cars having side sill elements, a flanged bumper and draft element

carried by the side sill elements and longitudinally slidable relative thereto, a cross member extending longitudinally across the bumper element between the flanges thereof and carried by said side sill elements against longitudinal movement relative thereto, and means including paired resilient elements carried between the flanges of the bumper element with the elements of each pair located on opposite sides of said cross member and each cooperating therewith to resist both bumping and draft forces acting upon the bumper element.

7. In a combined bumper and draft gear for mine or other industrial cars having side sill elements, a flanged bumper and draft element carried by the side sill elements and longitudinally slidable relative thereto, a cross member extending longitudinally across the bumper element between the flanges thereof and carried by said side sill elements against longitudinal movement relative thereto, and means including paired resilient elements carried between the flanges of the bumper element with the elements of each pair located on opposite sides of said cross member and cooperating therewith to resist both bumping and draft forces acting upon the bumper element, said means also including stops so constructed and arranged as to cause the elements of each pair of resilient means to sequentially resist the forces imposed on the bumper and draft element.

8. In a combined bumper and draft gear for mine or other industrial cars, a flanged bumper and draft element carried by the car and longitudinally slid able relative thereto, longitudinally spaced stops secured to the bumper flanges, a resilient unit located between said flanges and interposed between said stops and adapted to receive bumping and draft forces therefrom, and a single cross member retaining said bumper and draft element on the car and transferring both bumping and draft forces from the resilient unit to the car.

9. In a combined bumper and draft gear for mine or other industrial cars, a flanged bumper and draft element carried by the car and longitudinally slid able relative thereto, longitudinally spaced stops secured to the bumper flanges, a resilient unit located between said flanges and interposed between said stops and adapted to receive bumping and draft forces therefrom, said resilient unit including spaced apart springs, and a single cross member retaining said bumper and draft element on the car and extending through said resilient unit between the spaced springs and transferring both bumping and draft forces from the springs to the car.

10. In a combined bumper and draft gear for mine or other industrial cars, a flanged bumper and draft element carried by the car and longitudinally slid able relative thereto, a cross member extending across said element between the flanges thereof and connected to the car against longitudinal movement relative thereto, U-shaped straps located forward and rearward of said cross member and held thereby against movement away therefrom, resilient means interposed between said cross member and the web portions of said U-shaped straps and urging said straps away from the cross member, and means secured to said bumper and draft element for imposing draft and bump forces on said U-shaped straps.

11. In a combined bumper and draft gear for mine or other industrial cars, a flanged bumper and draft element carried by the car and longitudinally slid able relative thereto, a cross mem-

ber extending across said element between the flanges thereof and connected to the car against longitudinal movement relative thereto, U-shaped straps located forward and rearward of said cross member and held thereby against movement away therefrom, resilient means interposed between said cross member and the web portions of said U-shaped straps and urging said straps away from the cross member, and means secured to said bumper and draft element for imposing draft and bump forces on said U-shaped straps, said straps and means being so constructed and arranged as to cause all of said resilient means to resist both bump and draft forces.

12. In a combined bumper and draft gear for mine or other industrial cars, a flanged bumper and draft element carried by the car and longitudinally slid able relative thereto, a cross member extending across said element between the flanges thereof and connected to the car against longitudinal movement relative thereto, U-shaped straps located forward and rearward of said cross member and held thereby against movement away therefrom, resilient means interposed between said cross member and the web portions of said U-shaped straps and urging said straps away from the cross member, and means secured to said bumper and draft element for imposing draft and bump forces on said U-shaped straps, said straps and means being so constructed and arranged as to cause all of said resilient means to resist both bump and draft forces.

13. In a combined bumper and draft gear for mine or other industrial cars, a flanged bumper and draft element carried by the car and longitudinally slid able relative thereto, a cross member extending across said element between the flanges thereof and connected to the car against longitudinal movement relative thereto, U-shaped straps located forward and rearward of said cross member and held thereby against movement away therefrom, resilient means interposed between said cross member and the web portions of said U-shaped straps and urging said straps away from the cross member, and means secured to said bumper and draft element for imposing draft and bump forces on said U-shaped straps, said straps and means being so constructed and arranged as to cause all of said resilient means to resist both bump and draft forces.

14. As an article of manufacture, a resilient unit comprising opposed U-shaped straps having overlapping arms with elongated slots formed therein adapted to receive a cross member, cross bars joining together the side arms of each strap and forming stops adjacent the ends of the strap preventing separation of the straps, and a resilient member and follower interposed between the web of each U-shaped strap and the cross bar stops joining together the arms of the opposed U-shaped strap.

15. As an article of manufacture, a pair of interlocked straps adapted to receive resilient units and comprising opposed U-shaped members each having side arms joined together by a web and positioned with the side arms thereof overlapped by the side arms of the opposed strap, and cross-bars located substantially in common planes and joining the side arms of each strap together remote from the web and at a point closer to the web of the opposed strap than to the web of the strap to which they are attached.

ROBERT A. SHIELDS.
